UNITED STATES PATENT OFFICE.

WILHELM REINERS AND GUSTAV KAHLISCH, OF MUNICH-GLADBACH, GERMANY,
ASSIGNORS TO W. SCHLAFHORST & CO., OF MUNICH-GLADBACH, GERMANY.

PROTECTIVE THIMBLE FOR BOBBINS.

Application filed August 15, 1922. Serial No. 582,074.

To all whom it may concern:

Be it known that we, WILHELM REINERS, manufacturer, a subject of the German Republic, and residing at Munich-Gladbach, 5 Germany, Rheydterstrasse 48, and GUSTAV KAHLISCH, engineer, a subject of the German Republic, and residing at Munich-Gladbach, Germany, Weststrasse 4, have invented certain new and useful Improvements 10 in Protective Thimbles for Bobbins of which the following is a specification.

Our invention relates to improvements in protective coverings for bobbins, particularly those of the so-called bottle bobbin 15 type.

During transportation or storage the yarn body of bobbins is liable to damage by reason of many causes. Friction with other bodies results in weakening of the strands 20 and consequent breaks on the machine, while exposure results in an accumulation of dust and dirt and frequently in a fading of the color. For these reasons it is essential that each bobbin be protected by a thimble or 25 jacket which shall be at once strong, durable and easy of application and removal.

Such a device is illustrated in the accompanying drawing in which *a* represents the 30 yarn body, *b* the head of the bobbin, *c* its base and *t* the protective jacket.

In carrying out our invention we form a light hull of metal or other suitable material which substantially conforms to the shape of the yarn body, yet is large enough so that its 35 inner surface will not come into contact therewith at any point when in position.

At its base the jacket is provided with suitable means *e* on its inner circumference for engaging in a circumferential groove *d* provided on the base *c* of the bobbin. The 40 lower edge of the jacket may be spun back to give additional strength.

When the jacket is placed in position, the bobbin head *b* comes into contact with the convergent wall of the jacket at *a* and is 45 thereby centered. When in this position the retaining means *e* has come into gripping contact with the groove *d* and the bobbin is thereby maintained in its centered position. Since the base of the bobbin is of slightly 50 larger circumference than the yarn body, the latter is held free of contact with the jacket wall and is consequently protected from any possible damage.

We claim:

A protective covering for bottle-shaped bobbins consisting of a metallic thimble of slightly larger diameter than the yarn body and conforming substantially in shape therewith so that when in position the bobbin 60 head is centered and supported by the convergent end of the thimble and its base by the thimble wall, whereby the yarn body is withheld from contact with the thimble.

The foregoing specification signed at Co- 65 logne, Germany, this 29th day of July, 1922.

WILHELM REINERS.
GUSTAV KAHLISCH.
